UNITED STATES PATENT OFFICE.

GUSTAV BOESCH, OF DANBURY, CONNECTICUT.

CLIPPING MACHINE.

Application filed July 14, 1920. Serial No. 396,268.

To all whom it may concern:

Be it known that I, GUSTAV BOESCH, a citizen of the United States, and a resident of Danbury, in the county of Fairfield and 5 State of Connecticut, have invented an Improvement in Clipping Machines, of which the following is a specification.

This invention relates to the art of fur preparation, and with regard to its more 10 specific features to apparatus for severing the projecting hair from pelt above the fur.

One of the objects of the invention is to provide a fur preparing machine, which shall be simple and durable in construction, 15 and reliable in action.

Another object is to provide a machine of the above type, which shall speedily and effectively remove hair projecting above the surface of the fur proper, without danger 20 of damaging the fur.

Another object is to provide apparatus of the above type, which shall be readily adjustable even by an unskilled person for proper treatment of different kinds of fur, 25 and shall be substantially proof against mal-adjustment.

Another object is to provide apparatus of the above type, which shall automatically and reliably remove the severed hair from 30 the operating parts of the apparatus.

Another object is to provide a machine whose wearing parts are readily adjustable to restore satisfactory operation.

Other objects will be in part obvious and 35 in part pointed out hereinafter.

The invention accordingly consists in the features of construction, combinations of elements and arrangement of parts, which will be exemplified in the construction hereinafter set forth, and the scope of the application of which will be indicated in the following claims.

In the accompanying drawings wherein is shown one of various possible embodiments 45 of the several features of this invention,

Fig. 1, is a plan view of my machine.

Fig. 2, is a transverse sectional view taken along the line 2—2 of Fig. 1 and viewed in the direction of the arrow.

50 Fig. 3, is a longitudinal sectional view taken along the line 3—3 of Fig. 2 upon an enlarged scale.

Figs. 4, 5, 6, are detail views of the stationary knife element, and the means for mounting the same.

55

Fig. 7 is a side view on an enlarged scale showing the adjusting and locking means of my skin holding frame, and

Fig. 8 is an end view of the same on a similarly enlarged scale.

60

Fig. 9 is a side view partly in section of my bearing.

Fig. 10 is a top view of my bearing, the journal cap being removed, and

65

Fig. 11 is a front view of my rotary operating member.

Similar reference characters refer to similar parts throughout the different views of the drawings.

Referring now to the drawings and more particularly to Figs. 1 and 2, I have shown a base 1, for my machine, preferably resting on standards 2. Rigidly connected to the top of the base, preferably by casting integrally therewith are journal boxes 3, 4 and 5, which are aligned to support the power shaft 6, preferably extending beyond journal box 5 and having mounted upon such extension, a pulley 7 through which driving power may be applied.

70

I preferably employ a special form of bearing construction for shaft 6, which will be more fully described below.

75

Upon the shaft 6, I preferably secure by a key or equivalent means, the cylindrical hub 8 (see Fig. 3) of a rotary hair removing member or cutter. This rotary cutter preferably includes a plurality of equidistant blades 9, preferably integrally formed with the hub, each blade intersecting said hub 90 preferably along a helical line as at 10 in Fig. 11.

80

The operative edge 11 of each blade, is also preferably of helical form. The blade itself as shown at 12 in Fig. 3, is undercut, 95 that is, its width does not extend radially from the hub, but it is concave on its forward side along any section taken transversely thereof. The entire rotary member, that is, the hub 8 with the blades 9, is preferably integrally formed, lending itself thus to convenient manufacture as well as to durability and ruggedness of construction; and, as above set forth, each blade member

90

95

100

9, in being undercut as at 12, and in extending outwardly at a progressively increasing inclination with respect to the radius, permits of the formation at its outer end of a cutting edge or cutting blade section 11 which may thus, and preferably does, extend at an angle to the radius itself. In Fig. 3, in which the rotary cutting member 8 with its blades 9 is seen in end elevation, this relation of the extreme cutting ends or edges of the blades 9 is clearly shown, and it will be noted that upon rotation of the cutter in clockwise direction as viewed in this figure, each cutting end or blade section 11 of each blade is moved in a direction substantially coincident with or approaching its own plane. Each blade, when co-acting with the stationary knife element 13, hereinafter more clearly described, is thus enabled to bring about a precise and nice cutting action, and when operating upon pelts and fur-bearing skins, and particularly where very fine hairs have to be severed, it will be readily appreciated that efficiency and speed of operation, as well as uniformity in result, depend to a material extent upon a good and continuous severing and cutting action. By this feature of construction undesirable and ineffective or even partial twisting off, breaking and crunching action upon the hairs, which action would otherwise take place, is avoided. In this connection it might be noted that the locus or path of travel of the cutting edge or edges is a cylinder of revolution, and that the above efficient cutting action as distinguished from a crunching action is at least in part brought about because the plane of the cutting ends or edges of the blades 9 is directed into, and approaches coincidence with, the cylinder generated by the cutting edges. I preferably form the pitch of my helical edges 11 such that a plane through the center of my hub and the end of any blade will intersect an adjoining blade.

Mounted upon the base 1 is a slide 30 transversely adjustable of the machine by means hereinafter described. On this slide is a hair-box 16 encasing the upper portion of the rotary cutter and tapered into a discharge passage 17. The substantially cylindrical inner surface of the box and its general shape tend to produce the suction hereinafter referred to in detail, and the tapering conformation into the discharge or exhaust passage avoids recesses in which the hair clippings would tend to collect. This hair-box is secured to the slide as by the screws 103 and adjustment of the slide will correspondingly adjust the hair-box to bring it with its associated parts into proper relation to the edges of the cutters when the latter are sharpened and thus ground away. The ends of the hair box are substantially closed as by end walls 16 suitably

secured to the end portions of the member 16, and these end walls are preferably slotted horizontally, as at 16^b (see Fig. 3), to permit relative movement between the hair box 16 and the shaft 6 to take place when adjustments as hereinabove described are made.

Secured to a lug 19 near the top of the hair box, there is preferably provided a guide plate 20, whose lower edge 21 is somewhat above shaft 6 and extends substantially to the path of edges 11 on blade 9. It will thus be noted not only that the lower edge 21 of the guide plate 20 is closely adjacent the path of travel of the edges 11 on the blades 9, but also that the edge 14 of a stationary knife element 13, more clearly described hereinafter, is substantially coincident with an element of the surface of revolution made by the cutting edges of the blades of the rotary member 8; the aperture thus formed between the edges 21 and 14 is furthermore, as will be clear from Figure 3, relatively narrow so that the resultant aperture presents an effective opening in a direction tangential to the cylinder of revolution formed by the rotating cutting edges of the members 9, which tangential opening is so slight that substantially no air can be discharged through this small tangential opening by the centrifugal action produced by the rotating member 9. On the other hand, the discharge passage 17 is relatively large and presents a much greater effective tangential opening, thus permitting air that is pocketed on the concave sides of the blades 9 to be tangentially thrown out of the apparatus by centrifugal force. This difference in effective tangential openings, together with the rapidly rotating air-pocketing blades 9 of the rotary member 8, is effective to achieve an outward movement of air through the discharge passage 17 with a resultant inward movement of air through the aperture formed by the plate 20 and the knife element 13, and this inward movement of air through this latter aperture is in turn effective to draw the fine hair of the skin or pelt inwardly through the aperture and thus position it in the path of movement of the cutting edges 11 of the rotating blades 9. The guide plate 20 is preferably secured to the hair box by screws 21', extending through elongated slots 22 to permit adjustment. By this means the size of the aperture between the plate 20 and the upper cutting edge 14 of the knife element 13 may be adjusted, thereby to vary the velocity of inflow of air therethrough and thus to adjust at will the proper presenting of the individual hairs into the path of the cutting edges of the blades 9 of the rotary member 8, as is clearly shown in Fig. 3.

Mounted somewhat below the axis of the rotary operator, I provide a stationary knife 130

element 13, whose cutting edge 14 is parallel to shaft 6. The edge of blade 9 in operation, passes in close proximity to stationary edge 14, so that in view of its helical shape, the former will intersect knife 14 at only one point at a time, the point of intersection travelling from one end to the other of the stationary knife, producing a cutting rather than a shearing action. Thus, this nice cutting action, upon which reliability, continuity and speed of operation depend, results from the arrangement, hereinabove described of the cutting edges 11 in having their respective planes, instead of moving transversely past the stationary edge 14 of the cutting element 13, move in a direction approaching coincidence with the generated surface of revolution. Before any blade has completed its action the succeeding one will start effective operation in view of the pitch relation above set forth, thus making the cutting action continuous. As shown in Figs. 1 and 2 the ends of the rotary operator are preferably in close proximity to adjacent journal boxes 3 and 4.

I prefer to secure knife 13 in an inclined position, against inclined surface 104 of the knife holder or support 105 by the use of a frame made of two standards 23 and 24, bolted to the sides of the knife holder or support 105 as shown at 25 and 26 and further held against displacement by set pins 25' and 26', the sides of knife 13 being preferably bevelled as shown at 27, and the standards 23 and 24 having co-operating bevelled projections 28, fitting over the bevelled blade edges to tightly hold the same in position.

Each of the standards 23 and 24 is provided with a projection 29 against which the ends or edge of blade 14 abut, thus quickly and accurately locating the edge in its proper position for co-acting with the rotary cutter in clipping the hair. Thus it will be seen that whenever the knife element 13 is removed, as, for example, for purposes of sharpening its edge 14, or whenever the blade 13 is replaced, the edge thereof which coacts with the rotary cutter is at once positioned in or restored to its proper relation with respect to the rotary cutter, thereby avoiding the necessity of readjusting the knife-holder 105, the slide 30 or associated parts.

The knife holder or support 105 has its upper part preferably concave as shown at 106 to complement the inner surface of the hair-box. The edges 11 of the blades will thus pass in proximity to said concavity. The knife holder or support 105 is clamped to the slide 30 by a single screw 101 provided with a shoulder 106' abutting the lower surface of said slide, and the holder or support 105 may thus be pivoted about the axis of screw 101 and swung about this axis with

respect to the slide 30 on which the support or holder 105 rests. By this arrangement the upper edge 14 of the blade member 13 may be readily brought into parallelism with the axis of shaft 6 or into substantial coincidence with an element of the cylinder of revolution formed by the cutting edges 11 of the rotary member 8, it being understood that the holder or support 105 and immediately related parts are suitably formed or shaped with respect to one another to permit this pivotal adjustment of the holder 105 to take place. It might further be pointed out also that this pivotal adjustment will in general be of relatively slight extent.

I form the edges 11 of my rotary cutter, and edge 14 of my stationary knife sharp, so as to produce the cutting action above set forth in an efficient manner. Although I prefer to thus form my clipping elements with sharp edges, it is to be understood that the term "knife blade" or "knife element" as applied to the stationary member is to be broadly interpreted, to include a generally similar construction, intended to operate with a dull rather than a sharp edge, inasmuch as certain features and advantages of this invention may be achieved where the edge of this member 13 is dull rather than sharp.

The slide 30 with all parts mounted thereon is adjustable in position as shown in Fig. 3, to simultaneously bring the stationary knife and the guide plate into position for accurate cooperation with the rotary member 8.

I accomplish this, by providing a tapped transverse opening 34' in base 1, within which is threaded a feedscrew 34. This feedscrew has an unthreaded shank 35, passing through a downwardly extending lug 36 preferably integral with slide 30. A flange 38 on shank 35 rests against the inner surface of lug 36, and knurled head 37 of the feedscrew abuts the outer surface of this lug. It is thus seen that rotation of head 37 will cause feedscrew 34 to work out of its thread, whereby flange 38 moves lug 36 and with it knifeholder or support 105, hairbox 17 and slide 30 to the left, until the blade 13 and plate 20 simultaneously reach the proper position relative to the rotary element.

I provide a screw 31 extending vertically upward from below base 1, freely through slide 30 as at elongated slot 31', and threaded into knifeholder or support 105. This screw has a head 32 adapted to be firmly clamped against the bottom of base 1, to thereby rigidly secure slide 30 and its attached parts into their adjusted position. It will be noted, however, that tightening the screw 31-32 clamps the holder or support 105 and slide 30 rigidly to the base or frame member 1, and that the single clamping screw 31-32 permits the previously ad-

justed parts to be fixed in adjusted position in a highly convenient yet thoroughly reliable manner.

To place the skin to be treated in proper relation to the operating elements, and to hold it there for treatment, I provide a work carriage to be now described:

Two parallel rods, 39 and 40, are provided, extending transversely of base 1, one near each end of said base. Rod 39 passes through a corresponding opening in journal box 5, and rod 40 extends through a lug 41 cast upon base 1.

The base 1, is preferably provided with integral extensions 42 and 43, near the ends of which are provided integral upstanding perforated lugs 44 and 45, through which the rear end of rods 39 and 40 respectively, extend. Each rod thus passing through two aligned openings of substantially the size of the rod, these rods are kept in proper parallel alignment.

Secured to the forward ends of the rods 39 and 40 are fixtures 46 and 47 respectively 25 rigidly held in position thereon by means of suitable set screws each of said fixtures having a transversely extending stud 48 formed integrally therewith and adapted to receive the tubular cross member 49. The studs 48 of the fixtures 46 and 47 are of such diameter with respect to the inside diameter of the tubular cross member 49 that they may be readily forced therein to form a rigid connection with the fixtures 46 and 47 and hence 35 also with the rods 39 and 40. Thus a rigid unitary structure is formed with the rods 39 and 40 to facilitate the proper longitudinal movement of the rods 39 and 40 within their bearings. The cross member 49, being of tubular construction, makes for a maximum strength and rigidity together with a minimum of weight.

A skin supporting member 60, formed preferably of a suitable steel rod and bent into substantially the form as illustrated in Figure 1 to have its two ends 58 and 59 substantially parallel to each other and to provide a skin supporting section 60 thereof parallel to the shaft 6 is mounted upon 45 the rods 39 and 40 by means of suitable fixtures to permit of the adjustment of the skin supporting section 60 in a manner to be hereinafter described.

The adjusting and locking means for the skin holding frame 60 for securing the latter to the rods 39 and 40 are similar in construction and referring to Figures 7 and 8 wherein one of these means is illustrated on an enlarged scale, it will be noted that 55 I provide a split clamping member 50 mounted upon the rod 40 and adapted to be clamped firmly thereto by means of the cap screw 51. The clamping member 50 is provided with a vertical extension 52 which is 60 faced off to form a substantial bearing sur-

face for the machine face of an extension 53 of a second clamping member 54 adapted to receive the section 59 of the skin holding frame 60, the section 59 being securely clamped therein by means of the cap screw 55. A clamping screw 56 passes through the extension 53 of the clamping member 50, and it will be noted that the clamping member 54 with its associated skin holding frame 60 may be pivoted about the clamping screw 56 as shown in the dotted line position in Figure 7 and securely clamped in any such desired position. Such adjustment or rotation of the clamping members 54 about the clamping screws 56 permits of the adjustment of the skin supporting section 60 to the proper elevation with respect to the blades 9 and the cutting edge 14 of the knife element 13. The contacting faces of the clamping members 52 and 53 are of sufficient expanse so that the several associated parts are securely held in the desired adjusted position when the clamping screws 56 are tightened.

The pelt or skin supporting member 60 is adjustable with respect to the cutting elements by means of the clamping members 50 and 54 by means of which the clamping member 50 with its associated parts and the skin holding member 60 may be positioned at any desired location longitudinally of the rods 39 and 40. Furthermore the parallel ends 58 and 59 of the skin holding frame 100 may be adjustably positioned within the clamping members 54 to give the desired relation in a horizontal plane between the skin holding section 60 and the cutting elements.

It will thus be noted that the inward movement of the parallel rods 39 and 40 within their bearing members by reason of pressure applied to the frame at the cross member 49 causes a like inward movement toward the cutting element of the pelt supporting section 60. Such inward movement of the several parts may be accomplished by a like movement of the operator's body leaning against the cross member 49.

To compel return of the pelt holding construction to its original position, I preferably encircle rods 39 and 40 with coil springs 83 and 84 respectively, the rear ends of said coil springs contacting box 5 and lug 41 respectively and the forward ends contacting 120 collars 85 and 86 respectively, secured to the rods by set screws as shown at 87. The operator as is apparent may thus push the work carriage against the opposition of springs 83 and 84 through a distance depending on the length of the fur on the skin, the spring when compressed limiting the approach of the skin holding member toward the stationary knife.

Collars 88 are secured to each rod as by 130

set screws 88' to limit the return movement of the carriage toward inoperative position, by contact one with box 5 and the other with lug 41.

5 My bearings 89 are preferably of Babbitt metal and each is preferably provided with an external circumferential groove 92 into which extends a screw 93 which screw is threaded into cap 90. Any tendency of the 10 bearing to work its way longitudinally out of the box is thus avoided. To take up wear on the bearing, the same is preferably split longitudinally at one point as at 94, tightening of screw 93 serving to restore the proper 15 internal diameter of the partially worn bearing. It will be noted that I prefer to position the split bushing or bearing 89 in each of the posts 34 and 35 (see Figs. 1 and 9) so that the split in the bearings is on that side 20 of the shaft 6 remote from or substantially diametrically opposite the stationary blade member 13 with which the rotary cutting member 8 coacts. Thus, as the bearings 25 wear due to continued operation, the tightening of the screw 93, in contracting the bearing or bushing 89 about the shaft 6, acts to urge the shaft 6 with its associated cutting member 8 toward the right, as viewed in Fig. 9 and in Fig. 3, and thus there is made 30 compensation for the wear not only in the aligned bushings which support the shaft 6 but also in the wear that may take place at the cutting edges of the blade members 9, as well as the cutting edge 14 of the stationary 35 cutting element 13. Thus, a tightening of the bearings to compensate for wear is made to take place in such manner that the rotary cutting element is prevented from receding from the stationary blade or cutting element 13 and thus continued operation 40 may take place without necessitating a readjustment of either the cutting element 13 or its associated parts. A wing lock nut 95 serves to lock screw 93 in any position in 45 which it may be set. The journal box preferably has a separable cover 90 bolted in place as at 91 whereby the bearing is accessible for replacement.

50 The operation of my machine is substantially as follows:

The operator having adjusted the skin supporting rod 60 to the proper height by rotating the skin support rod 60 about the clamping screws 56 and by tightening the 55 latter screws after the proper adjustment has been made, places the pelt or skin to be treated upon the pelt supporting rod 60 with the fur extending outwardly or in the direction towards the cutting elements. He then 60 presses his body against the cross rod 49 and pushes the latter with its parallel rods 39 and 40 and skin support 60 inwardly until the skin comes into proper proximity to the cutting edge 14 and the blades 9 of the rotary cutting element 8. The dotted

line position as shown in Figure 1 is illustrative of such inward movement of the several parts. The cutting blades are preferably given a relatively high rate of speed by connection of the pulley 7 to a suitable 70 source of power, whereupon the operator then draws the pelt back and forth across the supporting rod 60.

The cutting element 9 rapidly rotating within the relatively snug hair box causes 75 a suction action to take place from the exterior past edge 14, into the cavity between the cutter hub and the hair box 17. This suction action, as already hereinbefore set forth, is brought about by reason of the fact that the effective tangential opening provided by the aperture between the plate 20 and the knife element 13 is so small with respect to the relatively large effective tangential opening furnished by the discharge passage 17, that air pocketed at the concave sides of the blades 9 of the rotary member 8 may be centrifugally and hence tangentially thrown outwardly into and through the discharge 80 passage 17 while a similar action cannot be effectively achieved at the aperture between the plate member 20 and the knife element 13, due to the fact that the effective tangential opening inherent in this aperture is too 85 slight; the movement of air out of the hairbox 16 and through the discharge passage 17 thus results in an inward movement of air (or suction) through the aperture between the plate 20 and the knife element 13. The 90 suction draws the hair to be severed inwardly past the edge 14, so that the helical edge 11 in cooperation with edge 14 may clip these hairs from the fur. This cutting action taking place in the manner hereinabove described is continuous, as the succeeding edge 11, begins to cooperate with knife edge 14, before any particular edge has passed the latter. I define the surface 95 of revolution generated by the cutter as 100 the locus of operation of said cutter.

In view of the rapid rotation of the cutter element within the relatively snug hair box and knife holder the air pocketed between two adjacent blades as they pass the concave surface of the knife holder or support 105 is centrifugally thrown outward, thereby effectively blowing the severed hair from the cutting edges and the hair box. The severed hair is thus blown out centrifugally 110 through the discharge passage 17.

It is thus seen that I provide a convenient rotary cutter element combined with a fan for cleaning out the hair box, or from another point of view I provide a fan construction with blades so arranged as to perform the hair clipping function. If I allowed my rotary cutter to operate within a hair box cavity materially larger than the 115 surface of revolution generated by said cut- 120

ter the pneumatic actions above set forth would not be satisfactorily realized.

After extended use of the device, as the bearings 89 or any of them, become worn, it is merely necessary to tighten screw 93 and lock it by means of wing nut 95 which action in virtue of the split construction of the bearing will reduce its inner diameter so as to fit it for proper operation.

10. When the rotary cutter element becomes dull, it can be sharpened in a manner which is obvious. This sharpening will, however, somewhat reduce the radius of the cutter. To make allowance for this reduction, it is merely necessary to loosen bolt 31 and to turn screw 34 by handle 37, thereby moving the slide 30 with the attached hair box 17, together with knifeholder or support 105, knife 13 and guide plate 20, to a small extent to place the latter two elements into cooperation with the cutter element in its somewhat reduced dimensions. Thereupon head 32 is turned to clamp the knifeholder and slide against base 1, in order to rigidly secure the elements in their adjusted position.

Stationary knife 13, may be further adjusted with respect to its holder or support 105 and guide plate 20 with respect to lug 19 in a manner which appears obvious. To secure parallelism of edge 14 with shaft 6, a swiveling adjustment of knife holder or support 105 about screw 101 as an axis, may be made and as already hereinbefore described.

It will thus be seen that there is herein described apparatus in which the several features of this invention are embodied, and which apparatus in its action attains the various objects of the invention and is well suited to meet the requirements of practical use.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

55. 1. In a hair-clipping machine, in combination, a rotary member having a cutting blade element spaced from the axis of rotation thereof and adapted upon rotation of said member to generate by its cutting edge a cylinder of revolution, said cutting blade element having the intersecting surfaces forming the cutting edge each curved to substantially merge into the surface of said cylinder of revolution, and a stationary knife element cooperating therewith.

2. In a hair-clipping machine, in combination, a rotary hub member having formed integrally therewith a plurality of cutting elements each comprising a substantially radially and outwardly extending rib portion gradually tapering outwardly and gradually bending over to terminate in a cutting blade portion formed by the intersecting surfaces of said rib portion, each of the said intersecting surfaces being directed substantially tangentially with respect to the surface of the cylinder of revolution generated by the cutting edge thereof, and a stationary knife element coacting therewith.

3. In a hair-clipping machine, a rotary cutter comprising a rotary member having a cutting blade element spaced from the axis of rotation thereof and adapted upon rotation of said member to generate by its cutting edge a cylinder of revolution, said cutting blade element having the intersecting surfaces forming the cutting edge each directed to be substantially tangential to the surface of the said cylinder of revolution at the line of intersection thereof with the surface of said cylinder of revolution.

4. In a hair-clipping machine, a rotary cutter comprising a rotary hub member having formed integrally therewith a plurality of cutting elements each comprising a substantially radially and outwardly extending rib portion gradually tapering outwardly and bending over to terminate in a cutting blade portion formed by the intersecting surfaces of said rib portion, each of the said intersecting surfaces being directed substantially tangentially with respect to the surface of the cylinder of revolution, generated by the cutting edge of said blade portion, at the line of intersection thereof with the surface of said cylinder of revolution.

5. In a hair-clipping machine, in combination, a rotatable cutter member, a stationary knife element cooperating therewith for cutting action, means for detachably mounting said stationary knife element adjacent said rotatable cutter member, and relatively fixed means associated with said mounting means and adapted to engage a portion of the active edge of the knife element for predetermining the position of and the alignment of said knife element within said mounting means and with respect to said rotatable cutter member.

6. In a hair-clipping machine, in combination, a rotatable member having a plurality of cutting edges, a stationary knife element cooperating therewith for cutting action and positioned substantially tangential with respect to said rotatable cutter member, means for detachably mounting said stationary knife element, and means adapted to engage the active edge of the knife element for fixing the position of the said

active edge of said knife element with respect to said rotatable cutter member.

7. In a hair-clipping machine, in combination, a rotatable cutter member, a knife element cooperating therewith for cutting action, means adapted to engage the active edge of said knife element at two spaced points thereof for preventing movement of said knife element within its own plane beyond a predetermined position with respect to said rotatable cutter member and adapted thereby to directly align the active edge of said knife element with respect to said rotatable cutter member, and means to permit adjustment of said rotatable cutter member and said knife element with respect to one another.

8. In a hair clipping machine, in combination, a rotatable cutter member, a pair of ways, a knife blade mounted within said ways for cooperation with said rotatable cutter member, means for preventing said knife blade from assuming a position within said ways beyond a predetermined limit with respect to said rotatable cutter member and means for forcing said ways toward each other to clamp said knife blade in position.

9. In a hair clipping machine, in combination, a horizontal shaft, a rotatable cutter member thereon, a carriage mounted to slide in a direction substantially at right angles to the axis of said shaft, a pair of ways on said carriage, a knife blade mounted within said ways, means for adjusting said carriage and hence said knife blade toward or away from the axis of said shaft, and fixed means associated with each of said ways for limiting the extent to which said knife blade may be moved along said ways to a predetermined position and adapted thereby to directly align the cutting edge of said blade with respect to said rotatable cutter member.

10. In a hair clipping machine, in combination, a rotatable cutter member, a pivotally mounted holder, a knife blade, means on said holder for detachably mounting said knife blade in a position for cooperation with said cutter member, means for locking said holder in a predetermined position about its pivot, and means for preventing the active edge of said knife blade from extending beyond the locus of operation of said rotatable cutter member.

11. In a hair clipping machine, in combination, a horizontal shaft, a rotatable cutter member thereon, a carriage adapted to be moved in a direction substantially at right angles to the axis of said shaft, means for moving said carriage, a knife holder on said carriage and pivotally mounted with respect thereto, a knife blade secured to said holder adapted to cooperate with said rotatable cutter member, and means for locking

said knife holder and said carriage in adjusted position.

12. In a hair clipping machine, in combination, a rotatable cutter member, a knife blade having a longitudinally extending cutting edge and lateral supporting edges, means comprising a pair of ways each adapted to engage one of said lateral supporting edges for mounting said knife blade in position to cooperate with said rotatable cutter member, and means for forcing said ways toward each other thereby, to clamp said knife blade in position.

13. In a hair clipping machine, in combination, a rotatable cutter member, a knife blade, a pair of ways for supporting said knife blade in position to cooperate with said rotary cutter member, means for adjusting said pair of ways with respect to the locus of operation of said rotatable cutter member thereby to adjust said knife blade with respect to said cutter member, and a limiting stop associated with each of said ways and positioned to engage the cutting edge of said blade for limiting the position within said ways of said knife blade.

14. In a hair-clipping machine, in combination, a rotary cutter comprising a rotary hub member having formed integrally therewith a plurality of helical cutting elements each comprising a substantially radially and outwardly extending rib portion gradually tapering outwardly and bending over to terminate in a cutting blade portion formed by the intersecting surfaces of said rib portion, each of said intersecting surfaces being directed substantially tangentially with respect to the surface of the cylinder of revolution, generated by the cutting edge of said blade portion, at the line of intersection thereof with the surface of said cylinder of revolution.

15. In a hair removing machine, in combination, a rotary cutter, a stationary knife element with which said cutter coacts and having an active edge and beveled lateral edges, a frame for supporting said knife having a part overlapping said beveled edges, and limiting stops for said knife, associated with said frame and adapted to predetermine the position which said knife may assume with respect to said rotary cutter.

16. In a machine of the class described, in combination, a rotatable cutter member and a stationary knife element cooperating therewith, a main frame comprising substantially two parallel rods, a pelt-holding member mounted upon said parallel rods, a pair of means for pivotally mounting said pelt-holding member upon said parallel rods to permit adjustment of said member vertically about said pivoting means with respect to said cutting members, as well as longitudinally of said rods, and clamping

means incorporated in said pivoted mounting means to permit said pelt-holding member to be locked in its adjusted vertical position about said pivoting means.

- 5 17. In a hair-severing machine, in combination, a rotatable cutter member, a stationary knife element cooperating therewith, a shaft for rotatably supporting said cutter member, a split bearing for rotatably supporting said shaft, and means operative upon said split bearing adapted to contract said bearing to take up wear therein and adapted upon contraction of said bearing to urge said shaft with said cutter member toward said stationary knife element.
- 10 18. In a hair clipping machine or the like, in combination, a shaft, a rotatable cutter member thereon, fixed bearings for said shaft, a stationary knife element cooperating with said rotatable member for cutting action, and means for adjusting said knife element about an axis at right angles to said shaft and substantially parallel to the plane of said stationary knife element.
- 15 19. In a hair clipping machine, or the like, in combination, a horizontal shaft, a

rotatable cutter member thereon, a slide, a knife support on said slide, a knife element secured to said support and a single screw substantially perpendicular to said slide for 30 securing said support to said slide, whereby said support with its knife element may be swiveled about said screw for adjustment.

- 20 20. In a hair-severing machine, in combination, a rotatable cutter member, a 35 stationary knife element cooperating therewith, a shaft for rotatably supporting said cutter member, a split bearing for rotatably supporting said shaft, means supporting said split bearing with the split therein on 40 that side of said shaft remote from said stationary knife element, and clamping means for contracting said split bearing to take up wear therein and acting upon said bearing to urge said shaft and said rotary 45 cutter member towards said stationary knife element.

In testimony whereof, I have signed my name to this specification this first day of July.

GUSTAV BOESCH.
